PHOTOGRAPHIC PROCESSING

Paul Raibourn, Southport, Conn.

Application January 13, 1947, Serial No. 721,780

3 Claims. (Cl. 95—2)

1

This invention comprises a method of accurately controlling penetration of a photographic film processing solution into a photographic emulsion.

The broad object of this invention is to provide a substantially automatic method whereby the penetration or diffusion of a processing solution into a photographic film emulsion can be accurately determined and controlled.

A more specific object of the invention is to provide a method of this type for determining and controlling the penetration of processing solutions into a particular emulsion layer of a multiple emulsion film such as a monopack film.

A more detailed object of this invention is to provide such a method for use with the method disclosed in my copending application Serial No. 720,931, filed January 8, 1947, now abandoned, for Method of Producing Color Separation Negatives.

Other and more detailed objects of the invention will be apparent from the following description of one mode of practising it, as well as practising it with the variations suggested.

This invention resides substantially in the steps and series of steps all as hereinafter set forth in detail in connection with the attached drawings illustrating one embodiment of the apparatus used with the method of this invention.

In the accompanying drawings,

Figure 1 is a diagrammatic and schematic view of apparatus with which the method may be practiced;

Figure 2 is a front elevational view of the film prepared in accordance with this invention;

Figure 3 is a cross-sectional view taken on the line 3—3 of Figure 2;

Figure 4 is a diagrammatic and schematic illustration of the remainder of the apparatus which when associated with the apparatus of Figure 1, provides a means for practising the method herein disclosed; and

Figure 5 is a chart illustrating certain principles involved in this method.

As disclosed in greater detail in my above mentioned application, but sufficiently disclosed herein to understand how this invention is utilized, in the processing of multiple emulsion films such as monopack film for the preparation of color separation negatives therefrom, the processing solutions after exposure of the film are selectively diffused into the emulsion layers. Such treatment of a monopack film will be assumed as an aid to disclosing this method.

A monopack film will be considered having a

2

transparent plastic base on which are superposed three emulsion layers separated by two gelatin layers. The bottom layer directly superposed on the plastic base comprises a red sensitive emulsion upon which in turn is coated a layer of clear gelatin and upon that a layer of green sensitive emulsion. Coated on the green sensitive emulsion is a yellow dyed gelatin layer, and on that layer is coated a blue sensitive or so-called "color blind" emulsion. Initially a motion picture monopack film will be considered such as that illustrated in Figures 2 and 3. It will comprise a physical structure 10 having one, or as more common, two sets of sprocket perforations 11 extending along the side edges thereof between which lies the picture area 12. This film, as pictorially illustrated in Figure 3, comprises the clear plastic base 14, the red sensitive emulsion 15, the clear gelatin layer 16, the green sensitive emulsion layer 17, the yellow dyed layer 18, and the blue sensitive layer 19. The relative arrangement of the layers is, of course, subject to variation by appropriate change, as is well understood in the art. It is equally well understood that the film of Figures 2 and 3 is a well known article of commerce.

Assume that a monopack film of this type has been correctly exposed, developed and fixed to form black and white silver images in each emulsion layer. Assume further that it is desired to produce color separation negatives from these three silver images. As set forth in the above mentioned application, it is possible to produce separation negatives from the layers 19 and 17 above and below the yellow dyed gelatin layer 18 by bleaching of all the images in the monopack to silver halide and exposing it to a blue light from below the layer 18 and redeveloping the images contained in the exposed layers. The silver halide image in the unexposed layer can now be removed by suitable and well known silver halide solvents.

However, the above optical method cannot serve to differentiate as between the layers 17 and 15 which are separated by the clear gelatin layer 16, or in a modification where a clear separating layer is not employed. Thus, later in the process when preparing color separation negatives from the green layer 17 and the red layer 15, it is necessary to selectively process these layers. For example, during the process as disclosed in the above entitled application, it becomes ultimately necessary to convert the image in the green layer 17 to a silver halide image and bleach or remove it without affecting the red layer 15. This in-

volves the selective diffusion or penetration of the solvent into the red layer, in which operation it is desirable to stop the penetration of the solvent as soon as the image is cleared from the layer.

The method of this invention provides a very simple and effective procedure for determining when the image in the green layer is clear so that the penetration of the solvent can be stopped. In accordance with this invention there is applied either during the original exposure or during later processing, a fixed frequency sine wave image on the film which can be likened to a sound track such as is commonly used in talking pictures. For example, a 1000 cycle fixed frequency sine wave sound track can be applied to the film by means of apparatus which is well understood by and available to the art for this purpose.

In accordance with this invention it is preferable to apply this sine wave record at any part of the space beyond the inner edges of the perforations 11. For example, the image can be impressed between the broken parallel lines, as indicated at 13 in Figure 2, where, as shown, it overlaps in part at least, the sprocket perforations at that side of the film. According to the assumed example, the green layer 7 is under consideration, the 1000 cycle sound track is printed in the green emulsion layer with green light through a sharp cutting green filter to form an image which has been diagrammatically illustrated at 20 in Figure 3. This confines the sound track to the middle emulsion layer 17, and of course, it is clear that this sound track should be printed in prior to any processing of the monopack, that is while it is still normally light sensitive. Exposure by green light insures that the record 20 will be confined to the green sensitive layer. This sound track 20 may be printed in by means of the variable density type of recording equipment so as to form a sound track which when developed would appear as indicated at 20 in Figure 5. The density of this sound track is preferably controlled so as to bear the proper relation to the density of the picture image in the green layer. The proper density can easily be determined by experience, it being recalled that the monopack has been assumed to be properly exposed. Skilled photographers will, therefore, by experience, very quickly know the required density for the sound track. As will appear later, the density of the sound track should be sufficient so that when all the silver therein has been reduced or dissolved out all the silver in the green emulsion layer will have been reduced or dissolved out. The densest portion of the sound track will, of course, depend upon the amplitude of the fixed frequency signal recorded in the sound track, and this amplitude will be selected to attain the above result.

The exposed monopack with its gelatin images of the scene photographed and of the sound track is then fed from a supply reel 21 into a developing tank 22 which has been divided into a series of imaginary zones A, B, C and D, as diagrammatically illustrated in Figure 1, through which the film 10 progresses successively over a series of guide rollers 23 and 24. At points intermediate the imaginary sections are provided film absorbing and supply devices, diagrammatically illustrated as frameworks 25, 30 and 31, suspended by means of a cable and weights 29 on overhead pulleys 28. Suspended from the framework are the upper guide rolls 26 and the lower guide rolls 27. The lower guide rolls 24 and 27

are suspended in the bights formed by the serpentine path of the film through the solution, and it will be assumed that the guide rollers 23 in each imaginary section are independently motor driven so that they can be operated at different speeds. Thus, if the film moving through section A is moving more rapidly than through the section B, the excess film will be stored on the framework 25 in an obvious and well known manner, in that the bight supporting the roller 27 for the first section will gradually increase in length.

For description, assuming that the film in the section B is moving more slowly than the film in the section C, then the film stored on the second framework will be absorbed therefrom by reduction in length of the bight for the frame 30. Assuming that the number of upper and lower sets of rollers on the frames 25, 30 and 31 can be increased as desired, a considerable capacity for storage and supply of film to make up the difference in speed between any two sections will be available, all as is well understood in the art.

As is clear from Figure 1, the film issues from each imaginary section and passes through the points P1, P2 and P3. At these points the pick-up mechanism of the left-hand portion of Figure 4 can be placed. Thus at the point P1 there is provided a light source 43 with a suitable lens system and slit, as is well known in the sound picture art, to focus the light on the sound track 20. Opposite this slit is placed a photo-electric cell 13 which is connected by the wires 34 to the input of a suitable vacuum tube amplifier 35. There is similarly disposed at the point P2 another light source lens system and slit 36 with cooperating photo-electric cell 37 feeding the input of the amplifier 35. Finally, at the point P3 is another light source lens system and slit 38 cooperating with the photo-electric cell 39 which feeds the amplifier 35. The output of the amplifier is connected by the leads 40 to suitably designed filters 41, 42 and 43, respectively feeding the loud speakers 44, 45 and 46, or other suitable forms of indicating devices such as meters for visual as distinguished from audible reading.

In processing the film in the tank 22, it is preferable to use a sub-proportional reducer or solvent so loaded as to be of slow diffusion rate, so that it will destroy the low densities faster than the high densities in the emulsion layer being treated, that is, in the assumed example, the green emulsion layer 17. As the film 10 progresses through the first imaginary section A, the sub-proportional reducer with which the tank 22 is charged will begin to penetrate the layer 17 (the blue record image in the top layer having previously been removed as explained above). As this reducer penetrates this layer it will begin to reduce the silver halide image, and being a sub-proportional reducer will clear out the image in the less denser areas more quickly than in the high density areas. Of course, this action will occur not only in the picture areas 12 of the film, but also in the sound track area. When the film reaches the pick-up point P1, the image in the sound track 20 will have been reduced and of course more rapidly in the lighter areas than in the denser or signal peak areas. The movement of the sound track past the pick-up point P1 will result in the generation of a pulsating current of a certain magnitude such as that represented by the curve P1R (see Fig. 5). This curve has been plotted with intensity or amplitude versus film length. As the same point on the film progresses through the

imaginary section B it will be further reduced so that by the time it reaches the point P2 the currents generated will be of lower magnitude as represented by the curve P2R, and finally at the point P3 the magnitude of the current will have 5 been further reduced, as represented by the curve P3R. Of course, ultimately when the image in the sound track has completely disappeared, the current in the output of the photocell 39 will not be pulsating but will be a direct current.

The different currents of all the photocells will be mixed and fed to the amplifier where they are amplified to the desired degree and then fed selectively through the filters 41, 42 and 43, so as to operate the indicating devices 44, 45 and 46. 15 It will be assumed that the filter 41 is designed so that the device 44 reads the signal of the photoelectric cell 33 and the device 45 will read the signal of photocell 37, and the device 46 will read the signal of the photocell 39. Thus the operator by reading the signals of the devices 44, 45 and 46 can control the speed of operation of the film in the various sections so that when the film 10 emerges at the exit end of the tank 22 the image in the green emulsion layer will have completely 20 disappeared while insuring that the film has not remained in the solution any longer than is necessary to attain this result. Those skilled in the art will understand that the use of a sub-proportional reducer has the effect of first reducing the 25 low densities very rapidly, and then at the end clearing up the high density areas very rapidly, since in the meantime they have become low density areas.

As a further explanation, it will be noted that if by experience the signal of the device 44 indicates that at this point the image is disappearing too slowly, the film speed in the section A can be slowed down and vice versa, if the image is disappearing too rapidly the film speed can be increased. As the speed of the film in each of the imaginary sections can be independently controlled, it is clear that an experienced operator reading the signals of the devices 44, 45 and 46 can so control the overall speed of the film 10 30 through the tank 22 that it can be caused to issue from the tank at just the right time, that is just after complete reduction of the image in the green layer. This provides insurance against diffusion or penetration of the reducer into any of the other layers beyond the very minimum penetration which necessarily is inherent in processing of this type.

It should be noted in passing that the selection of three points P1, P2 and P3 was made for descriptive purposes, since in some cases only two conversion points may be necessary, and in others more conversion points may be necessary.

It is obvious that if the sound track 20 overlaps the perforations 11 of the film the movement of these perforations through the conversion point will generate a pulsating current to a frequency characteristic determined by the speed of the film. Thus there will be generated in each photo-electric cell a current corresponding to those perforations, and in designing the amplifier 35 and the filters 41, 42 and 43 provision can be made to completely suppress this component of the signal so that it will not appear at the indicating devices 44, 45 and 46.

It is, of course, recognized that changing the speed of movement of the film through the solution will cause some change in pitch of all the signal components generated at the pick-up point, but this will not disturb the usefulness of 75

the process since the operator is particularly interested in the magnitude of the components as indicated by the devices 44, 45 and 46 rather than the frequency thereof.

It is also apparent to those skilled in the art that the process herein disclosed is not limited to determining and controlling the reduction of the image in only one emulsion layer as by simple duplication of this mechanism it can be made to indicate the penetration of the solvent and the reduction of the image in different layers, in which event the frequency of the sound track signal would preferably be different for each layer, in which event frequency as well as amplitude of the indicated current would be read in order to understand the progress of reduction in each layer.

Those skilled in the art will also appreciate that this process is not limited to use in a system where the film moves. For example, the same principles can be applied in the processing of still pictures as distinguished from motion pictures, in which case the monopack film would as before be provided with a sound track. However, as the film would be stationary during processing, a spot of light can be made to move with respect to the sound track rapidly over the length thereof by suitable mechanical or optical means, so as to produce the same relative movement of film and light spot, with the result that the rate of reduction of the silver image could be read and processing stopped when the signal disappears.

It is apparent, therefore, that the subject matter of this invention is capable of application with various forms of equipment, all of which are well known to those versed in this art. I do not, therefore, desire to be limited to the details of the process herein disclosed, or by reason of a particular apparatus by means of which the process is practiced, but preferably the scope of my invention is to be determined by the appended claims.

What is claimed is:

1. A method of indicating the penetration of a processing solution into an emulsion layer of a multiple emulsion film, comprising the steps of exposing said film to form a latent scene image in each layer and to form a variable density signal image in at least one layer, the density of said signal image being substantially equal to the maximum density of said scene image, processing said film to form silver images of all of said exposures, bleaching said film, processing said film to reduce the density of all of the images in the layer containing said signal image, continuously moving said film during said last processing step, converting said signal image at successive time intervals of the reducing process to sensible signals indicative of the extent of reduction of the scene image at said intervals, and varying the relative rate of movement of said film in zones between successive points represented by said successive time intervals whereby complete reduction is attained at the time the film reaches the last conversion point.

2. A method of processing an exposed undeveloped multiple emulsion film, comprising the steps of printing a signal track in the form of a variable density record of a fixed frequency signal of predetermined magnitude in one of the layers of said film, the density of said signal track being substantially equal to the maximum density of exposure in that layer, developing and fixing said film, bleaching said film, processing said film to reduce the density of all the images in the

layer containing said signal track, and converting the signal track image at successive stages of development into sensible signals to indicate when the images in that layer have been reduced to a desired extent.

3. A method of processing an exposed undeveloped multiple emulsion film, comprising the steps of printing a signal track in the form of a variable density record of a fixed frequency signal of a magnitude to produce a density in the sound track substantially equal to the maximum density in the scene image in one of the layers of said film, the density of said signal track being substantially equal to the maximum density of exposure in that layer, developing and fixing said film, bleaching said film, processing said film to reduce the density of all the images in the layer containing said signal track, and converting the signal track image at successive stages of development into sensible signals to indicate 20

when the images in that layer have been reduced to a desired extent.
